[57] CLAIM

The ornamental design of a reusable extension for zipper pulls, as shown and described.

DESCRIPTION

FIG. 1 is a top view of the open reusable extension for zipper pulls of this invention;

FIG. 2 is a front view of the open reusable extension for zipper pulls of this invention;

FIG. 3 is a right side elevation view, the left side elevation being a mirror image of FIG. 3;

FIG. 4 is a rear view of the open reusable extension for zipper pulls of this invention;

FIG. 5 is a bottom view of the open reusable extension for zipper pulls of this invention;

FIG. 6 is a plan view of the closed reusable extension for zipper pulls of this invention;

FIG. 7 is a top view of the closed reusable extension of zipper pulls of this invention;

FIG. 8 is a front view of the closed reusable extension for zipper pulls of this invention;

FIG. 9 is a right side elevation view, the left side elevation being a mirror image of FIG. 9;

FIG. 10 is a rear view of the closed reusable extension for zipper pulls of this invention; and,

FIG. 11 is a bottom view of the closed reusable extension for zipper pulls of this invention.
